UNITED STATES PATENT OFFICE.

PERLEY F. HAZEN, OF ST. JOHNSBURY, VERMONT, ASSIGNOR TO THE E. & T. FAIRBANKS & COMPANY, OF SAME PLACE.

DESIGN FOR A SCALE-BEAM.

SPECIFICATION forming part of Design No. 24,480, dated July 16, 1895.

Application filed May 31, 1895. Serial No. 551,333. Term of patent 14 years.

To all whom it may concern:

Be it known that I, PERLEY F. HAZEN, a citizen of the United States, residing at St. Johnsbury, in the county of Caledonia, State 5 of Vermont, have invented a certain new and original Design for Scale-Beams, of which the following is a description, reference being had to the accompanying drawing, and to the letters of reference marked thereon.

10 My invention relates to a design for a scale-beam, and the same is illustrated in the accompanying drawing, in which the figure represents in side elevation a beam of the shape and configuration which forms the essential 15 feature of my design.

In the drawing, A represents the beam as a whole, having the substantially-rectangular portion *a* formed on a straight line on its under side, but having on its upper edge the vertically-projecting portion *b* at a point to one side the center of the entire beam. To the right of this vertical projection *b* the upper surface of the beam is provided with a series 20 of V-shaped notches arranged at suitable intervals out to the point *c*, from which point to the end of the beam the upper surface is 25 in a straight line. To the left of the vertical projection *b* the upper edge of the beam is

straight for a short distance, the vertical projection, however, merging into the straight 30 portion in a curved line *d*, while beyond this straight portion the beam is provided with a series of small notches extending for a short distance. At the points *e* and *f* of the beam, which points are opposite each 35 other, the beam is enlarged on the convex curves *g*, which extend to the points *h*, where a slight shoulder is formed, and thence to the end of the beam extend two convex curves, which meet in the point *i*, forming the configuration of the end of the beam shown.

Extending outwardly from the edge of the beam below the vertically-projecting portion *b* are two oval knife-edge studs.

Having thus described my invention, what 45 I claim, and desire to secure by Letters Patent, is—

The design for a scale beam as herein shown and described.

In testimony whereof I affix my signature 50 in presence of two witnesses.

PERLEY F. HAZEN.
